(57) CLAIM

The ornamental design for an electric oil pump for an engine, as shown and described.

DESCRIPTION

FIG. 1 is a front elevated view of an electric oil pump for an engine showing my new design.

FIG. 2 is a rear elevated view of the electric oil pump for an engine.

FIG. 3 is a right side elevated view of the electric oil pump for an engine.

FIG. 4 is a left side elevated view of the electric oil pump for an engine.

FIG. 5 is a top plan view of the electric oil pump for an engine; and,

FIG. 6 is a bottom plan view of the electric oil pump for an engine.

It being understood the break lines indicate continuation of the cord uniformly along a length.
